DANIEL MCFARLAN MOORE, OF NEWARK, NEW JERSEY, ASSIGNOR TO MOORE ELECTRICAL COMPANY, OF NEW YORK, N. Y., A CORPORATION OF NEW YORK.

VACUUM-TUBE LAMP.

1,010,668.

Specification of Letters Patent.

Patented Dec. 5, 1911.

Application filed January 5, 1905. Serial No. 239,727.

To all whom it may concern:

Be it known that I, DANIEL MCFARLAN MOORE, a citizen of the United States, and a resident of Newark, in the county of Essex 5 and State of New Jersey, with post-office address 52 Lawrence street, have invented certain new and useful Improvements in Vacuum-Tube Lamps, of which the following is a specification.

10 My invention relates to devices ordinarily termed vacuum tubes, comprising a sealed inclosure for a gas or vapor through which electric energy is passed for the purpose of rendering the contents of the tube luminous 15 or for other purposes.

The invention relates more particularly to such tubes when operated by alternating currents, and the object is to provide for the operation of the same at lower voltages 20 than are permissible when my invention is not employed.

The invention consists in providing means for heating a portion of the electrode at each end of the tube by current independent of 25 the discharge current passed through the same from end to end thereby rendering each electrode more efficient as a cathode by reducing the difference of potential between the same and the gas at those instants of 30 time when the said electrode is required to operate as a cathode.

My invention consists also in an improved compound electrode one portion of which acts as a cathode and the other as an anode, 35 and also in the improved combinations of devices now particularly hereinafter described and then specified in the claims.

In the accompanying drawings Figure 1 is a vertical section through one end of a 40 tube embodying an electrode in one of the forms that may be employed. Fig. 2 shows diagrammatically one way of connecting the same to a circuit. Fig. 3 is a transverse section through the supporting stem for the 45 electrode.

1 is the gas or vapor containing tube through which electric energy is passed from end to end in the usual manner, one end only of said tube being shown. The 50 electrodes at the ends are each constructed preferably with a central portion 2, which becomes highly heated by the discharge, and which acts mainly as the cathode at every other alternation or when the current is of 55 proper direction, and with a surrounding

portion 3 which is less highly heated during operation and which acts mainly as an anode. The portion 3 may be made of graphite or other conductor and the portion 2 comprises preferably a filament of carbon 60 whose terminals are joined respectively to any suitable source of heating current adapted to render the same incandescent. The portion 3 may be in the form of a cup or cylinder suitably joined to a leading in wire 65 4, and the portion 2 has its ends secured respectively to leading in wires 4 and 5 passing through the glass stem 6 projecting through the base of the cup 3. Connection between leading in wire 4 and the electrode 70 3 is preferably made in the following manner: Stem 6 and the filament 2, may be the same as in an ordinary incandescent lamp. Connected to the leading in wire 4 at the inner end of the stem is a wire 12, 75 which is carried back and preferably wrapped around the stem 6. Surrounding the stem is a conducting cylinder 13 of carbon or graphite or other material bisected longitudinally on the line 14. The two 80 halves of the cylinder are bound back upon the stem by means of the binding wire 15. Forming a part of the cylinder is a collar or flange 16, upon which the perforated base 17 of the electrode 3 is supported. The 85 cylinder 13 is preferably made of graphite, and the wire 12 and binder 15 are preferably made of Norway iron which has been treated by heating it at a high temperature to drive out its occluded gases, previously to placing 90 it within the lamp. The binder 15, firmly presses the cylinder 13 against the wire 12, and forms connection between said cylinder and wire. These parts are assembled upon the stem in a suitable manner and then the 95 same is inserted into the glass tube of the lamp and fused to the base thereof at the point indicated at 18. Afterward the electrode 3 is slipped into the tube and by resting in contact with the flange 16 is in electrical connection with the cylinder 13, wire 12, and leading in wire 4. The alternating current which passes through the tube from end to end may be obtained by conversion 100 from alternating current mains 8, 8' the secondary 9 of the converter having its terminals connected respectively to the electrodes at the opposite ends of the tube, and being adapted to supply comparatively high voltage. Heating current for the portion 110

2 of the electrode at each end of the lamp and of suitable amperage but independent of that which passes from end to end is obtained from the mains 8, 8' through conversion by a converter the secondary of which is indicated at 10, but might be obtained from any other source. As will be seen the portion 2 is also connected to the same pole of secondary 9 as portion 3 of the electrode. Portion 2 is, therefore, heated not only by the discharge current circulating in the tube but is also locally heated by the current from 10. Portion 3 is heated by the discharge current only.

15 As will be seen the device is particularly suited for use on alternating current circuits, the part 2 being at all times very highly heated, and ready to act as the cathode, its temperature being maintained by the local heating source over the intervals when the current is flowing in reverse direction and during which it ceases to operate as a cathode.

I do not limit myself to any particular form of the parts making up the electrode but prefer the form shown for the reason among others that the part 3 protects the tube 1 from the heat of the part 2.

30 My invention may obviously be employed with tubes containing in some form a substance capable on decomposition of releasing a gas suitable for being ionized and rendered luminous by the electric energy passing through the tube from end to end.

35 What I claim as my invention is:—

1. In a vacuum tube lamp an electrode comprising a cylinder or cup of conducting material and a conductor located within the same combined with means independent of 40 the discharge for heating the said conductor.

2. In a vacuum tube, the combination of an electrode made in two parts or portions, both of which are connected to the same terminal and may operate both as the cathode 45 combined with a source of alternating current and means for converting said current into currents of different voltage fed respectively to the two portions of the cathode as a whole and to one portion thereof at a 50 lower voltage to heat the same locally.

3. In a vacuum tube, a glass stem provided with leading in wires for a filament in combination with a connecting wire wrapped around said stem and joined to one 55 end of said leading in wires within the tube, a bisected cylinder of conducting material clamped upon said stem and an internal electrode supported by said cylinder.

4. In an internal electrode vacuum tube, 60 the combination of a glass stem supporting

an incandescent filament suitably sealed to the base of the tube, and a cup shaped electrode having a central perforation substantially concentric with said stem, and electrically connected to one of the leading in 65 wires.

5. In a vacuum tube, a compound internal electrode comprising an incandescent conductor joined to leading in wires by which it may be furnished with local heating current, and a cylindrical discharge receiving electrode having connections with one of the leading in wires within the tube. 70

6. In a vacuum tube, the combination with a working electrode therefor made in two 75 parts or portions, one part consisting of an incandescent conductor mounted upon the other part and a source of electric energy for heating said incandescent conductor locally during its operation as a discharge 80 receiving portion of the electrode.

7. The combination with the electrode for a vacuum tube, of an incandescent conductor mounted on the same and forming a part 85 of the discharge receiving surface of said electrode and means for passing a local heating current through the incandescent portion, as and for the purpose described.

8. A compound electrode for a vacuum tube comprising a main discharge receiving 90 portion and a supplemental portion consisting of a conducting filament mounted on the main portion combined with a transformer having a secondary connected to both portions of the electrode and means for furnishing alternating currents at a lower tension to the conducting filament, as and for 95 the purpose described.

9. In a vacuum tube, the combination with a locally heated electrode of a transformer 100 secondary for supplying heating current and an independent secondary having its terminals connected respectively to the electrodes by which current is passed through the contained gas or vapor. 105

10. A vacuum tube provided with a conductor at each end operating as an electrode, each conductor having its ends connected to a source of alternating current independent of that supplying the other, a third source 110 of alternating current connected to one of each of said conductors.

Signed at New York in the county of New York and State of New York this 30th day of December, A. D. 1904.
